[57] CLAIM

The ornamental design for a wrist-worn cardiac monitor, as shown and described.

DESCRIPTION

FIG. 1 is an isometric view, slightly enlarged relative to FIGS. 2 through 6, of a wrist-worn cardiac monitor showing our new design;
FIG. 2 is a right side elevational view, with a wrist band being shown in broken lines for illustrative purposes only;
FIG. 3 is a front elevational view, the rear elevation being a mirror image thereof, with a wrist band being shown in broken lines for illustrative purposes only;
FIG. 4 is a top plan view;
FIG. 5 is a left side elevational view; and,
FIG. 6 is a bottom plan view.

FIG. 1

FIG. 3

FIG. 4

FIG. 2

FIG. 6

FIG. 5
